C. McGINN.
ADVERTISING DEVICE.
APPLICATION FILED DEC. 30, 1919.

1,383,828.

Patented July 5, 1921.

UNITED STATES PATENT OFFICE.

CHARLES McGINN, OF CLEVELAND, OHIO.

ADVERTISING DEVICE.

1,383,828.

Specification of Letters Patent.

Patented July 5, 1921.

Application filed December 30, 1919. Serial No. 348,458.

To all whom it may concern:

Be it known that I, CHARLES McGINN, a subject of Great Britain, residing at Cleveland, in the county of Cuyahoga, State of Ohio, have invented a new and useful Advertising Device, of which the following, in connection with the accompanying drawing, is a specification.

The objects of the invention are to provide a simple and practical method of arranging advertising matter upon the frame of a mirror, where the advertisements will attract the attention of all who pass in front of the frame.

This is especially useful as an advertising medium in barber shops, where the advertisements will be observed by a constantly changing procession of people. The invention includes perforated flexible bands or members, attachable at any convenient points, such as at their extremities, to the frame, and to which advertising signs or cards can be readily attached, by means of suitable metal fasteners passing through said perforations at any selective points.

In this manner an extremely convenient apparatus can be quickly installed, upon which cards or signs of various sizes can be adjusted and detachably secured at pleasure.

The invention is illustrated in the accompanying drawings, is hereinafter more fully described, and specifically pointed out in the claims.

In the accompanying drawings Figure 1 is an elevation showing a frame with three mirror glasses, illustrating the use of flexible bands attached to the frame upon which the advertising matter is supported; Fig. 2 is a similar view showing small chains employed for this purpose; Fig. 3 is a longitudinal section of the frame showing a band with advertising cards attached thereto; Fig. 4 is a plan view of a chain capable of use in this device; Fig. 5 is a plan view of a perforated band or ribbon; Fig. 6 is a transverse section of a perforated metal band and card, showing the manner of detachably securing the advertising cards thereto; Fig. 7 shows the perforated corner of an advertising card.

This invention is an improvement upon the device shown and claimed in my prior Letters Patent No. 739,019, granted to me Sept. 15, 1903, in which rigid wooden slats

are secured to a mirror frame, and to which the advertising matter is attached by tacks or nails.

The advantages of this device over the former device in convenience of use and storing and transportation are much greater, since the chains and flexible metal ribbons can be packed in a very small compass and can be easily carried, whereas the wooden bars or slats require a good deal of space for storage and they are too cumbersome to be readily adjusted to position.

In the drawings A represents the mirror frame; B, B, are perforated flexible metal bands which are tightly stretched in parallel position from one corner of the frame to another, and are attached thereto by means of screws or hooks C, C, which are passed through the perforations D, D, in the bands B, B.

To attach the cards E, E, to the bands they are perforated at F, F, preferably at the corners, in position to register with the perforations in the bands, and small flexible metal fasteners G, G, are passed through the perforations in the cards and bands and then the points of the fasteners are bent backward as shown in Fig. 6.

In Fig. 1 metal bands or ribbons are shown attached to the top, sides and intermediate bars of the mirror frame.

In Fig. 2 small chains are employed in like manner. The openings in the chains H, H, are close enough together to make the attachment of the cards possible at any point.

The side and intermediate bands or chains are attached to the lower band or chain at the top of the frame by hooking them thereto at 11 and by nails or screws at the lower end.

The cards may be perforated if desired at the time of hanging them.

Having described the invention, what I claim as new and desire to secure by Letters Patent is:

1. In a display device for advertising cards, the combination with a mirror, of flexible members having spaced openings therein, and attached in parallel lines to the top, side and intermediate bars of the mirror frame, advertising cards perforated in the margin to register with the openings in said members, and flexible metal fasteners, in-

sertible through the openings in said cards and members.

2. In an advertising device, the combination with a mirror, perforated flexible bands detachably attached to the top, side and intermediate bars of the mirror frame, the side and intermediate bands secured to the lower band of the top series, advertising cards, and metal fasteners insertible through

the perforations in said cards and bands, 10 all substantially as shown and described.

In testimony that I claim the invention above set forth I affix my signature in the presence of two witnesses.

CHARLES McGINN.
